UNITED STATES PATENT OFFICE

CHARLES M. WILKERSON, OF MIDDLEFIELD, OHIO

WRENCH

Specification of Letters Patent

Patented July 29, 1919.

1,311,850

Application filed April 16, 1919. Serial No. 290,435.

To all whom it may concern:

Be it known that I, CHARLES M. WILKERSON, a citizen of the United States, and a resident of Middlefield, in the county of Geauga and State of Ohio, have invented a new and Improved Wrench, of which the following is a full, clear, and exact description.

The present invention relates to new and useful improvements in wrenches, and has for its primary object to provide a device of this character by means of which a firmer grip upon the article operated upon may be obtained.

15 A further object of the invention is to so construct the wrench as to make it capable of use in connection with pipes and other cylindrical articles, in addition to its use with nuts and the like as an ordinary monkey wrench.

With the above and other objects in view, reference is had to the accompanying drawings in which—

Figure 1 is a side elevation of the wrench showing one of the positions thereof;

Fig. 2 is a similar view showing the several parts in another position;

Fig. 3 is an edge view of the device; and

Fig. 4 is a transverse sectional view on the line 4—4 of Fig. 2.

Referring more particularly to the drawings, the device comprises a jaw member 10 and a handle member 11. The jaw member 10 and handle member 11 are pivotally connected together, as at 12, the jaw member 10 being bifurcated, as at 13, and the handle member 11 being reduced, as at 14, to lie between the bifurcations of the jaw member 10.

40 The reference character 15 designates one of the jaws of the wrench, and said jaw is rigidly carried by the jaw member 10. The reference character 16 designates the movable jaw of the wrench, and is provided with 45 a screwthreaded extension 17, which operates through an internally screw-threaded nut 18 as in the ordinary form of monkey wrench. This internally screw-threaded nut 18 is mounted in a recess 19 in a housing 50 20, and said housing is provided with spaced depending flanges 21, which are adapted to receive the pivoted ends of the jaw member

10 and the handle member 11. The depending flanges 21 of the housing 20 are provided with spaced perforations 22, which are preferably circular in form, and adapted to be received within said perforations 22 are pins 23 and 24. These pins 23 and 24 are carried by the jaw member 10 and the handle member 11, respectively, and are of smaller diameter than the perforations 22, which permits of a rocking movement of the housing 20 relative to the jaw member 10 and handle member 11.

The operation of the device is as follows: The jaws 15 and 16 are engaged with the article operated upon, and the nut 18 is rotated until the jaw 16 grips said article. The handle member 11 is now grasped and if moved about the pivot 12, its pin 24 engages the walls of its respective recess 22, and movement of the handle 11 to a position where it is in longitudinal alinement with the jaw member 10, causes the movable jaw 16 to firmly grip the article with which it is engaged. When the handle member 11 is moved in the opposite direction, it will be seen that the jaw member 16 will be withdrawn from engagement with the article with which it was previously engaged, thus permitting of removal of the wrench.

By this construction, it will be seen that a monkey wrench is constructed in which a movement similar to that provided by the well-known "Stillson" wrench is obtained, thus rendering the device capable of use both as an ordinary monkey wrench and as a pipe or rod wrench which is capable of use with bodies of circular cross sectional form.

Having thus described the invention, what is claimed as new is:

1. A device of the character described comprising a stationary jaw, a handle pivotally carried thereby, a pin carried by said stationary jaw, a pin carried by the handle, said pins being arranged on opposite sides of the pivotal connection of the stationary jaw and the handle, a housing provided with apertures of larger diameter than said pins and adapted to receive the same whereby the said housing is rocked relatively to the stationary jaw and the handle upon

movement of the latter, and a jaw adjustably carried by said housing and movable with respect to the stationary jaw upon movement of the handle.

5 2. In a wrench, a rigid jaw, a plurality of pins projecting from opposite sides thereof, a handle pivotally secured to said rigid jaw, a plurality of pins carried by the op-

posite sides of said handle, a housing provided with apertures adapted for receiving 10 the pins of the rigid jaw and the pivoted handle, said apertures being of greater dimensions than the pins received therein, and a jaw adjustably carried by said housing.

CHARLES M. WILKERSON.
